UNITED STATES PATENT OFFICE.

CLARENCE E. GIDNEY, OF SAWTELLE, CALIFORNIA.

CLOSURE LATCH.

Application filed April 14, 1925. Serial No. 23,020.

To all whom it may concern:

Be it known that I, CLARENCE E. GIDNEY, a citizen of Canada, residing at Sawtelle, in the county of Los Angeles and State of California, have invented certain new and useful Improvements in a Closure Latch, of which the following is a specification.

This invention relates to an improved latch for closures, the same being especially, but not necessarily, designed for use upon doors, and particularly those types employed in houses.

What I aim to do is to provide a spring projected latch bolt confined within a casing, the casing being such as to permit it to be fitted into a mortise in the door to conceal it.

In order that a complete understanding of the invention will be had it is deemed advisable to set forth the method of assembly of the improved structure. To this end it is to be stated that one method of assembly would be by inserting the unit comprising the parts 8, 9, 10 and 11, through the open end of the casing, after which the internal rib shown could be depressed inwardly; or, the plunger 8 may be inserted by itself, and then the rib pressed in and the spring and head 10 placed in position.

The latch bolt itself is novel in that it is adjustable in length, and also for the reason that it is constructed to accommodate a commonly marketed knob which may be readily connected thereto to serve as a handle for opening the door, and also as a means for retracting the latch to unlock the door.

The particular details forming this novel structure will become apparent from the following description and drawings.

In the accompanying drawing forming a part of this application, and in which like numerals are employed to designate like parts throughout the same:

Figure 1 is a fragmentary elevation of a portion of a door and its frame showing the improved latch in association therewith.

Figure 2 is a central longitudinal section through the device showing the particular details clearly.

In the drawing, the reference character 1 designates a door or other suitable swinging closure, and the reference character 2 designates the frame with which it is cooperable. As shown in Figure 2 this frame is provided with a keeper seat 3, and with a facing and keeper plate 4 of ordinary construction. In

order to adapt the door for the improved fastener, it is provided with a relatively small centrally located mortise and with an elongated guide slot 5 opening through the inner face and into the mortise. Fitted snugly into this mortise is an elongated and relatively small casing 6 having a slot 7 in one side registering with the slot 5. The outer open end of the casing is fashioned in any appropriate way to finish it off and to provide a means for screwing or otherwise fastening it in place. Between its ends, the casing is formed with an inwardly pressed annular channel 7 providing an internal stop rib. Mounted for sliding movement in the casing is a spring projected plunger, and the plunger preferably comprises a head 8 of a cross section corresponding to that of the casing and a stem 9 extending from the center of the head. The free end of the stem is screw threaded, and is adapted to be screwed into a screw threaded socket formed in the tongue 10. This permits the plunger to be shorted within comparatively small limits so that the distance of projection of the tongue may be regulated to some extent. Surrounding the stem 9 and interposed between the tongue and the rib 7 is a coil spring which serves to normally project the plunger outwardly. Particular emphasis is to be laid on the head 8 which is provided in one side with a screw threaded socket of a predetermined diameter.

As before stated, the gist of the invention resides in the fact that the device is confined wholly in the mortise to conceal it. It is equally as important, if not more so however that the device is such as to accommodate a commonly marketed knob 12. This knob is of conventional configuration, and in most circumstances is made of glass and carries a central bolt 13 screw threaded at its inner end. My device is important in that it permits this commonly marketed article to be bought and connected with the head 8 through the medium of the screw threaded socket with which it is provided. Sufficient adjustment may be made for the necessary clearance between the knob and the surface of the door. In this way a handle is provided for opening and closing the door and also for retracting the tongue 10 from the keeper seat to unlock the door.

The advantages derived from a device embodying these novel characteristics are clearly apparent, and the details and construc-

tion of the device itself are likewise apparent. In view of this it is believed that a more lengthy description is not necessary.

While the preferred embodiment of the invention has been shown and described, it is to be understood that minor changes coming within the field of invention claimed may be resorted to.

Having thus described the invention, what I claim as new is:

1. In a closure fastener of the class described, a casing and a spring pressed plunger slidable in said casing, said plunger comprising a head provided with a central stem screw threaded at its free end, a tongue having a screw socket in its inner end into which said threads are tapped, and a coiled spring surrounding said stem and bearing against said tongue at one end, said casing being provided with a stop with which the other end of the spring is engaged.

2. In a closure fastener of the class described, an open ended plunger casing adapt-

ed for reception in a mortised socket, said casing being provided in one side with a longitudinal guide slot and being formed between its ends with an annular channel forming an internal rib, a spring pressed plunger located in said casing and comprising a head carrying a stem screw threaded at its free end, a bevel ended tongue provided with a socket into which the screw threaded end of said stem is tapped, and a coiled spring surrounding said stem, and bearing at one end against the tongue and at its opposite end against said rib to yieldably hold said head in engagement with said rib when said plunger is projected, and said head being provided in one side with a screw threaded socket of a predetermined depth and diameter adapted for reception of a standardized knob-bolt.

In testimony whereof I affix my signature.

CLARENCE E. GIDNEY.
